VALVE MECHANISM FOR AIR-BRAKE APPARATUS.

No. 893,261.

Specification of Letters Patent.

Patented July 14, 1908.

Application filed December 17, 1906. Serial No. 348,266.

To all whom it may concern:

Be it known that I, FRANKLIN A. PIERCE, a citizen of the United States of America, residing at Wheeling, in the county of Ohio and State of West Virginia, have invented certain new and useful Improvements in Valve Mechanism for Air-Brake Apparatus; and I hereby declare the following to be a full, clear, and exact description of the invention, such as will enable others skilled in the art to which it pertains to make and use the same.

This invention relates to improvements in valve-mechanism for air-brake apparatus, and pertains more especially to an air-brake in which is employed a so-called triple-valve-mechanism which controls the supply of air from the auxiliary reservoir to the brake-cylinder and also the exhaust from the brake-cylinder.

The object of this invention is to provide air-brake apparatus wherein, although the auxiliary reservoir is recharged while the brake-cylinder is operating to apply the brake and hold the latter applied in and upon the partial or gradual application of the brake, full communication between the auxiliary reservoir and the brake-cylinder in the case of an emergency may be instantaneously established to at once fully apply the brake.

In the accompanying drawings, Figure 1 is a side elevation largely in central vertical section of air-brake apparatus comprising valve-mechanism embodying my invention. In this figure the pistons and valves of the said valve-mechanism are shown in their normal and brake-releasing position. Fig. 2 is a side elevation, mostly in central vertical section, showing the said pistons and valves in their brake-applying position in the partial or gradual application of the brake. Fig. 3 is a vertical section on line 3—3, Fig. 1, looking in the direction indicated by the arrow. Fig. 4 is a side elevation, mostly in central vertical section, illustrating the position of the aforesaid valves and pistons upon the instantaneous application of the brake.

Referring to the drawings, A indicates the valve-casing of so-called triple-valve-mechanism. The casing A is provided interiorly with a chamber 10. A piston B snugly fits within and is adapted to move endwise of the chamber 10. The chamber 10 is arranged horizontally, and the valve-casing A is pro-

vided interiorly and below the said chamber with a port 12 which communicates at its upper end with the outer end of the chamber 10 and at its lower end with a horizontally arranged pipe C. The port 12 constitutes the 60 train-pipe-pressure inlet of the chamber 10.

The valve-casing A is provided at the inner end of the chamber 10 with a valve-seat 13 which is arranged horizontally and parallel with the travel of the piston B, and a correspondingly arranged single-ported slide-valve b is mounted on or engages the seat 13 and rigid or operatively connected with the piston B, said valve being provided in its under side and next to the seat 13 with a 70 port 14.

The valve-casing A is provided interiorly with two ports 15 and 16 which extend from the seat 13 and are spaced longitudinally of the travel of the valve b. The port 15 communicates with the pipe D employed in conducting reservoir-pressure to the brake-cylinder (not shown). The pipe D constitutes therefore the brake-cylinder-supply pipe. The port 16 communicates with the external 80 atmosphere and therefore constitutes an exhaust-port.

The valve-casing A is provided interiorly and next externally of the valve b with a chamber 17 which communicates with the 85 chamber 10 at the inner end of the latter and extends to the valve-seat 13 at the free end of the valve in any position of the valve.

E indicates the auxiliary reservoir which is provided with an outlet e which communicates with the chamber 17 and consequently with the chamber 10 at the inner end of the latter, and f represents a pipe which communicates with and is employed in supplying train-pipe-pressure to the reservoir. The 90 reservoir-outlet e, the chamber 17 and the port 15 form a passageway adapted to establish communication between the reservoir E and the pipe D, and the ports 14, 15 and 16 form a passageway adapted to exhaust the 95 pipe D, and the valve b controls continuity in the said passageways.

The piston B is arranged to operate between the port 12 and the reservoir-outlet e, and the relative arrangement of the parts is 105 such that when the piston B is in its normal position at the inner end of the chamber 10, as shown in Fig. 1, communication between the reservoir E and the pipe D is interrupted and communication between the said pipe D and 110

the exhaust-port 16 established so that the brake is released, and when the aforesaid piston has moved far enough toward the outer end of the said chamber,—that is, toward the 5 adjacent end of the port 12,—as shown in Figs. 2 and 4, communication between the pipe D and the exhaust-port 16 is interrupted and communication between the said pipe and the reservoir E established so that the brake 10 is partially or fully applied, and that the said piston is actuated by the train-pipe-pressure and reservoir-pressure in opposite directions respectively, being moved by the train-pipe pressure preparatory to the release of the 15 brake and by the reservoir-pressure preparatory to the application of the brake.

G represents a pipe for supplying train-pipe-pressure, which pipe has its discharging end arranged in line endwise with and a suitable distance from the pipe C, and a valve-casing H is interposed between and attached to the said pipes C and G. The valve-casing H is provided interiorly and a suitable distance above the adjacent ends of the pipes C 20 and G with a vertically arranged chamber 20. A piston K snugly fits within and is adapted to move endwise of the chamber 20. The upper or outer end wall of the chamber 20 is provided with a port 22 which constitutes the fluid-outlet and train-pipe-pressure 25 inlet of the said chamber.

The valve-casing H is provided interiorly with a vertically arranged bore 23. The bore 23 is arranged centrally of the lower end of 30 and connects with the chamber 20. The bore 23 extends downwardly from the chamber 20 to a point a suitable distance below the adjacent ends of the pipes C and G and is snugly engaged by a double-ported slide- 35 valve k which is movable endwise of the said bore and is rigid or operatively connected with the piston K. The bore 23 communicates at its lower end,—that is, at the free end of the valve k,—with a port 24 which is arranged centrally of the said end of the said 40 bore and constitutes the pressure-inlet and fluid-outlet of the said bore during the operation of the valve k. The port 24 is in communication with the pipe f, and consequently 45 the bore 23 is in communication at the free end of the valve k with the reservoir E.

The valve k is provided centrally between its ends with a horizontally arranged port 50 which extends transversely of and through 55 the valve. The valve k is provided in one side thereof centrally between the port 25 and the free end of the valve with a port 26 which extends longitudinally of the valve a suitable distance.

60 The valve-casing H is provided with two horizontally arranged ports 27 and 28 which are arranged in line endwise at opposite sides respectively of the travel of the valve k and communicate with the pipes G and C re- 65 spectively.

The valve-casing H is provided interiorly with a way 30 which communicates at one end with the valve-port 26 and at its other end with the valve-casing-port 28. The way 30 is provided with a suitably applied and 70 suitably confined valve I which controls continuity in the said way and is arranged to open in the direction required to permit the passage of fluid from the valve-port 26 to the valve-casing-port 28. The valve-port 26 is 75 long enough to communicate with the valve-casing-port 30 in any position of the valve.

The valve-casing H is provided interiorly adjacent the way 30 with another way 32 which at one end connects and is adapted to 80 communicate with the valve-port-connecting end of the way 30 at a point between the valve I and the valve-port 26, and at its other end is connected and communicates with the bore 23 at the free end of the valve k and 85 with the pipe f. The way 32 is provided interiorly with a valve J which controls continuity in the said way and is arranged to open in the direction required to permit the passage of pressure from the way 30 at a 90 point between the valve I and the valve-port 26 to the bore 23 and pipe f.

The valve-casing H is provided interiorly of its upper end, between the chamber 20 and the valve-casing A, with a horizontally 95 arranged chamber 40. A piston L snugly fits within and is adapted to move endwise of the chamber 40. A way 42 communicates at one end with the chamber 40 centrally of the outer end of the said chamber and 100 communicates at its other end with the port 24, way 32 and pipe f. The chamber 40 is consequently in communication at its outer end with the reservoir E. The valve-casing H is provided above and exteriorly of the 105 chamber 20 with a valve-seat 43 which is arranged horizontally and parallel with the travel of the piston L, extending from the chamber 40 to and over the chamber 20. A correspondingly arranged four-ported slide- 110 valve l is mounted on or engages the seat 43 and is rigid with or operatively connected with the piston L, said valve being provided with three ports 44, 45 and 46 which extend vertically through the valve, and having an 115 exhaust-port 47 which is arranged between the outer and central vertical ports 44 and 45 and extends from the valve-seat 43 to one side of the valve where it is adapted to communicate (see Fig. 3) through an exhaust-port 49 formed in the valve-casing H with the external atmosphere.

The valve-casing H is provided interiorly and next externally of the valve l with a 125 chamber 48 which communicates with the chamber 40 at the inner end of the latter and extends to the valve-seat 43 at the free end of the said valve in any position of the valve.

Two ways 50 and 52 are formed in the 130

valve-casing H at opposite sides respectively of the chamber 20. The way 50 communicates at one end with the chamber 48 at the outer end of the chamber and communicates at its other end with the valve-casing-port 27. The way 52 communicates at one end with the valve-port 46 and at its other end with the valve-casing-port 28. A valve m contained within the way 52 controls continuity in the said way and is arranged to open in the direction of the valve-port 46 to permit the passage of fluid through the said way from the valve-casing-port 28 toward the chamber 48 and into the latter through the valve-port 46. The port 46 extends longitudinally of the valve l far enough to maintain communication between the way 52 and the chamber 48 in any position of the valve. The chamber 48 establishes communication between the chamber 40 and the way 50.

A stop for limiting the movement of the valve l and connected piston L in the direction of the outer end of the chamber 48 is provided and preferably formed by the head r of a horizontally arranged and endwise shiftable stem R which extends through a stuffing-box 55 with which the valve-casing H is provided around the said stem. The outer end of the stem R is screw-threaded externally, and a correspondingly threaded nut 56 is mounted on the said end of the said stem at the outer end of the stuffing-box 55. The nut 56 forms a stop to limit the inward movement of the stop-forming head r of the stem R, and a spiral spring x is mounted and confined on the stem R between the head r and the inner end of the stuffing-box 55, which spring acts to retain the said stem in its inner and normal position.

Preferably a spring y is confined between the top of the valve l and the top wall of the chamber 48 and acts to retain the valve in proper engagement with the valve-seat 43. It will be observed that the valve-casing-port 27, valve-port 25, valve-casing-port 28, pipe C and port 12 are instrumental in the formation of a passageway between the train-pressure-supply pipe G and the chamber 10, and continuity in the said passageway is controlled by the valve k.—The valve-casing-port 27, way 50, chamber 48, valve-port 44 and valve-casing-port 22 are instrumental in the formation of a passageway between the train-pressure-supply pipe G and the chamber 20, and continuity in the said passageway is controlled by the valve l. The valve-casing-port 27, way 50, chamber 48, valve-port 46, way 52, valve-casing-port 28, pipe C and port 12 are instrumental in the formation of a passageway between the train-pressure-supply pipe G and the chamber 10, and continuity in the said passageway is controlled by the valve m. The valve-casing-port 27, the valve-port 26, the

valve-port-connecting end of the way 30, the way 32, and the way 42 are instrumental in the formation of a passageway between the train-pressure-supply pipe G and the outer end of the chamber 40, and continuity in the said passageway is controlled by the valve k. The valve-casing-port 27, valve-port 26, the valve-port-connecting end of the way 30, the way 32 and the pipe f are instrumental in the formation of a passageway between the train-pressure-supply pipe G and the auxilairy reservoir, and continuity in the said passageway is controlled by the valve k.

In the normal and brake-releasing position of the piston B and connected valve b, (as shown in Fig. 1) the piston K is in its normal position at the lower or inner end of the chamber 20 and the valve k is in position with its port 25 in communication with the valve-casing-ports 27 and 28 and with its port 26 out of communication with the port 27.

In the normal and brake-releasing position of the pistons B and K and connected valves the piston L is in its normal position within the outer end of the chamber 40 and the valve l is removed from the stop r and in position with its port 44 in communication through the valve-casing-port 22 with the chamber 20 and with its exhaust-port 47 out of communication with the exhaust-port 49 in the valve-casing.

In the normal and brake-releasing position of the pistons K and L and connected valves the chamber 20 is in communication through the valve-casing-port 22, valve-port 44, chamber 48, way 50 and valve-casing-port 27 with the train-pressure-supply pipe G, and the chamber 10 is in communication through the port 12, pipe C, valve-casing-port 28, valve-port 25 and valve-casing-port 27 with the said train-pressure-supply pipe.

A reduction in the train-pipe-pressure results in the application of the brake. To partially or gradually apply the brake the train-pipe-pressure is first reduced just enough to move the valve l into contact with the stop r and this reduction in the train-pipe-pressure obviously results in a reduction of the air-pressure within the chambers 10, 20 and 40 so as to result in the actuation of the pistons B, K and L and connected valves into a brake-applying position, as shown in Fig. 2, by the reservoir-pressure against the piston B next the valve b, against the face of the piston L at the outer end of the chamber 40 and against the lower or free end of the valve k. Upon the actuation of the pistons and connected valves to partially or gradually apply the brake, as shown in Fig. 2, the valve l is in contact with the stop r, as already indicated, with its port 44 out of communication with the valve-casing-port 22 and consequently out of communication with the chamber 20, and with

its exhaust-port 47 in communication with the exhaust-port 49 in the valve-casing, and the valve *k* is in position with its port 25 out of communication with the valve-casing-ports 27 and 28 and with its port 26 establishing communication between the valve-casing-port 27 and the way 30. Consequently while the brake is being held applied the auxiliary reservoir *E* may be recharged 10 by pumping air into the train-pressure-supply pipe *G* and in thus recharging the reservoir air under pressure passes from the train-pipe-pressure supply-pipe *G* through the valve-casing-port 27, valve-port 26, way 15 30 and pipe *f* into the reservoir. Of course during the recharging of the reservoir *E* the air-pressure at both ends of the chambers 10 and 40 become equal. Upon a partial application of the brake, as shown in Fig. 20 2, a further and full application of the brake is had by a further reduction in the train-pressure-supply pipe to the extent required to actuate the stop *r* by the valve *l* against the action of the spring *x* far enough to 25 bring the valve-port 45 into communication through the valve-casing-port 22 with the chamber 20 and thereby effect a further reduction of the pressure in the passageway connecting the chamber 48 with the chamber 10 and formed, as already indicated, by the valve-port 46, way 52, valve-casing-port 30 28, pipe *C* and port 12.

For a full and instantaneous application of the brake as required in the case of an emergency, the full travel of the pistons *B* and *L* and connected valves is at once effected without moving the piston *K* and connected valve *k* by instantaneously reducing the train-pipe-pressure to such an extent that 40 the valve *l* is at once brought from the position shown in Fig. 1 into position to bring its port 45 into communication through the valve-casing-port 22 with the chamber 20, as shown in Fig. 4.

45 It will be observed therefore that my valve-mechanism may be operated to fully and instantaneously apply the brake as well as to partially and gradually apply the brake and permit of a recharging of the auxiliary reservoir during and upon the partial or gradual application of the brake.

Referring again to the movement of the pistons *B*, *K* and *L* to partially or gradually apply the brakes, I would here remark that 55 the construction and arrangement of the parts are such that the piston *B* in its brake-releasing position has enough less surface exposed to the auxiliary-pressure than to the train-pipe-pressure that the train-pipe-pressure 60 sure in the chamber 10 is a few pounds greater than the pressure in the chamber 17, whereas the piston *L* has an equal pressure upon both faces thereof, so that a reduction of, for instance, one-half pound pressure in 65 the train-pipe will cause the piston *L* to

move so as to place port 47 over port 22, resulting in the elevation or movement of the piston *K* to a retaining and recharging position. In other words, because the pressure in the chamber 10 is somewhat greater 70 than in the chamber 17 in the brake-releasing position of the piston *B* the said reduction of pressure in the train-pipe will result in the movement of the pistons *L* and *K* before the piston *B* begins to move into its brake-applying position. 75

What I claim is:—

1. In valve-mechanism for air-brake apparatus, the combination, with the auxiliary reservoir having an outlet; the brake-cylinder-connecting pipe; a pipe for supplying train-pipe-pressure, and a valve-casing provided interiorly with a chamber having a train-pipe-pressure-inlet; a piston snugly fitting within and movable endwise of the chamber and in its normal and brake-releasing position arranged a suitable distance from the said inlet, which piston is arranged between and exposed to the train-pipe-pressure and reservoir-pressure and adapted to 80 be actuated by the reservoir-pressure and train-pipe-pressure in opposite directions respectively; a slide-valve operatively connected with the piston, and a seat for the valve, the valve and valve-casing being ported and chambered as required to exhaust the brake-cylinder-connecting pipe in the normal and 85 brake-releasing position of the piston and to establish communication between the outlet of the auxiliary reservoir and the said pipe upon the actuation of the piston to the extent required by the reservoir-pressure, of means whereby, upon a reduction of the train-pipe-pressure to partially or gradually apply the 90 brake, the aforesaid piston being actuated by the reservoir-pressure and the reservoir is recharged during and upon the said actuation of the piston by the reservoir-pressure. 95

2. In valve-mechanism for air-brake apparatus, the combination, with the auxiliary reservoir having an outlet; the brake-cylinder-connecting pipe; a pipe for supplying train-pipe-pressure, and a valve-casing provided interiorly with a chamber having a train-pipe-pressure inlet; a piston snugly fitting within and movable endwise of the said chamber and in its normal and brake-releasing position arranged a suitable distance from the said inlet, which piston is arranged between and exposed to the train-pipe-pressure and reservoir-pressure and adapted to 110 be actuated by the reservoir-pressure and train-pipe-pressure in opposite directions respectively; a slide-valve operatively connected with the piston; a seat for the said valve, and a chamber formed next externally of the valve and extending from the first-mentioned chamber to the valve-seat at the free end of the valve and being in communication with the reservoir-outlet, the valve and valve-cas- 115 120 125 130

ing being ported as required to exhaust the brake-cylinder-connecting pipe in the normal and brake-releasing position of the piston and to establish communication between the 5 second-mentioned chamber and the said pipe upon the actuation of the piston to the extent required by the reservoir-pressure, of means instrumental in recharging the reservoir from the train-pressure-supply pipe during and upon the actuation of the aforesaid piston by the reservoir-pressure upon a reduction of the train-pipe-pressure to partially or gradually apply the brake.

3. In air-brake apparatus, the auxiliary 15 reservoir; the brake-cylinder-connecting pipe; a pipe for supplying train-pipe-pressure; a chamber 10 having a train-pipe-pressure inlet; a piston snugly fitting within and movable endwise of the said chamber and in 20 its normal and brake-releasing position arranged a suitable distance from the said inlet, which piston is arranged between and exposed to the train-pipe-pressure and reservoir-pressure and adapted to be actuated by 25 the reservoir-pressure and train-pipe-pressure in opposite directions respectively; means whereby the brake-cylinder-connecting pipe is supplied with air under pressure from the reservoir upon the actuation of the 30 piston to the extent required by the reservoir-pressure and is exhausted upon the actuation of the piston by the train-pipe-pressure, and means instrumental in recharging the reservoir from the train-pipe-pressure-supply pipe during and upon the actuation of the 35 aforesaid piston by the reservoir-pressure upon a reduction of the train-pipe-pressure to partially or gradually apply the brake.

4. In valve-mechanism for air-brake apparatus, the combination, with the auxiliary 40 reservoir; the brake-cylinder-connecting pipe; a pipe for supplying train-pipe-pressure; a valve-casing provided interiorly with a chamber having a train-pipe-pressure inlet; a 45 piston snugly fitting within and movable endwise of the said chamber and in its normal and brake-releasing position arranged a suitable distance from the said inlet, which piston is arranged between and exposed to the 50 train-pipe-pressure and reservoir-pressure and adapted to be actuated by the reservoir-pressure and train-pipe-pressure in opposite directions respectively; a slide-valve operatively connected with the piston; a seat for 55 the valve, and a chamber formed next externally of the valve and extending from the first-mentioned chamber to the valve-seat at the free end of the valve and being in communication with the reservoir-outlet, the 60 valve and valve-casing being ported as required to exhaust the brake-cylinder-connecting pipe in the normal and brake-releasing position of the piston and to establish communication between the second-mentioned chamber and the said pipe upon the 65

actuation of the piston to the extent required by the reservoir-pressure, of means whereby full communication between the brake-cylinder-supply pipe and the reservoir may be instantaneously established by a sudden reduction of the train-pipe-pressure to the extent required and whereby by a reduction of the train-pipe-pressure to gradually establish the said communication to partially or gradually apply the brake the aforesaid piston is actuated by the reservoir-pressure and the reservoir is recharged during and upon the said actuation of the piston by the reservoir-pressure.

5. In valve-mechanism for air-brake apparatus, the combination, with the auxiliary reservoir; the brake-cylinder-supply pipe; a pipe for supplying train-pipe-pressure, and a valve-casing provided interiorly with the following:— a chamber having a train-pipe-pressure inlet; a piston snugly fitting within and movable endwise of the said chamber and in its normal and brake-releasing position arranged a suitable distance from the said inlet, which piston is arranged between 90 and exposed to the train-pipe-pressure and reservoir-pressure and adapted to be actuated by the reservoir-pressure and train-pipe-pressure in opposite directions respectively; a slide-valve operatively connected with the 95 piston; a seat for the valve, and a chamber formed next externally of the valve and extending from the first-mentioned chamber to the valve-seat at the free end of the valve and being in communication with the reservoir, the valve and valve-casing being ported as required to exhaust the brake-cylinder-supply pipe in the normal and brake-releasing position of the piston and to establish communication between the second-mentioned 100 chamber and the said pipe upon the actuation of the piston to the extent required by the reservoir-pressure, of a valve-casing interposed between the train-pipe-pressure-supply pipe and the aforesaid inlet and provided with the chambers 20, 40 and 48, the bore 23, the ports 22, 24, 27, 28 and 49, and the ways 30, 32, 42, 50 and 52; the pistons K and L; the valve k having the ports 25 and 26; the valve l having the ports 44, 45, 46 and 47, 110 and the valves I, J and m, all arranged and operating substantially as shown and described.

6. In valve-mechanism for air-brake apparatus, the combination, with the auxiliary 120 reservoir; the brake-cylinder-supply pipe; a pipe for supplying train-pipe-pressure, and a valve-casing provided interiorly with the following:— a chamber having a train-pipe-pressure inlet; a piston snugly fitting within and movable endwise of the said chamber and in its normal and brake-releasing position arranged a suitable distance from the said inlet, which piston is arranged between 125 and exposed to the train-pipe-pressure and 130

reservoir-pressure and adapted to be actuated by the reservoir-pressure and train-pipe-pressure in opposite directions respectively; a slide-valve operatively connected with the 5 piston; a seat for the valve, and a chamber formed next externally of the valve and extending from the first-mentioned chamber to the valve-seat at the free end of the valve and being in communication with the reservoir, the valve and valve-casing being ported as required to exhaust the brake-cylinder-connecting pipe in the normal and brake-releasing position of the piston and to establish communication between the second-mentioned 10 chamber and the said pipe upon the actuation of the piston to the extent required by the reservoir-pressure, of a second valve-casing interposed between the train-pipe-pressure-supply pipe and the aforesaid inlet 15 and provided with the chambers 20, 40 and 48, the bore 23, the ports 22, 24, 27, 28 and 49 and the ways 30, 32, 42, 50 and 52; the pistons K and L; the valve k having the ports 25 44, 45, 46 and 47; the valves I, J and m; the shiftable stop r and the spring x, all arranged and operating substantially as shown and described.

7. In valve-mechanism for air-brake apparatus, the combination, with an auxiliary reservoir E; a brake-cylinder-supply pipe D; a pipe G for supplying train-pipe-pressure, and a valve-casing A provided interiorly with the following:— a chamber 10 having a train-pipe-pressure inlet; a piston B within the said chamber; a slide-valve b operatively connected with the piston; a seat for the valve, and a chamber 17 formed next externally of the valve and extending from the first-mentioned chamber to the valve-seat at the free end of the valve and being in communication with the reservoir, the valve and valve-casing being ported as required to exhaust the brake-cylinder-supply pipe in the 40 normal and brake-releasing position of the piston and to establish communication between the second-mentioned chamber and the said pipe upon the actuation of the piston to the extent required by the reservoir-pressure, of a valve-casing H interposed between the train-pipe-pressure-supply pipe and the aforesaid inlet and comprising a chamber 20 having a combined inlet and outlet 22 at one end; a piston K within the last-mentioned 45 chamber; a bore 23 connecting at one end with the other end of the last-mentioned chamber, which bore is in communication at its other end with the auxiliary reservoir; a double-ported slide-valve k engaging the said

bore and operatively connected with the last-mentioned piston, which valve is provided with a transverse port 25 and a side port 26; two ports 27 and 28 formed in the second-mentioned valve-casing at opposite sides respectively of the travel of the double-ported valve and communicating the one with the train-pipe-pressure-supply pipe and the other with the inlet of the piston-containing chamber of the first-mentioned valve-casing; a slide-valve-seat formed within the second-mentioned valve-casing externally of the aforesaid piston-containing chamber of the said valve-casing; a chamber 40 arranged at one end of the last-mentioned valve-seat and in communication at its outer end with the aforesaid bore at the free end of the double-ported valve and with the reservoir; a piston L within the last-mentioned chamber; a slide-valve l engaging the last-mentioned seat and operatively connected with the last-mentioned piston; a suitably valved way 52 communicating at one end with the train-pipe-pressure-supply pipe and at its other end with the aforesaid inlet of the piston-containing chamber of the first-mentioned valve-casing; a suitably valved way 30 communicating at one end with the last-mentioned inlet and at its other end with the side-port of the double-ported valve in either position of the latter; a suitably valved way 32 arranged to receive air under pressure from the said side port and communicating with the reservoir and with the aforesaid bore at the free end of the double-ported valve and with the second-mentioned piston-containing chamber of the second-mentioned valve-casing at the outer end of the said chamber, and a passage-way establishing communication with the last-mentioned piston-containing chamber and the train-pressure-supply-pipe, 100 and the valve connected with the piston in the last-mentioned chamber and the second-mentioned valve-casing being ported as required to exhaust the first-mentioned piston-containing chamber of the said valve-casing during the gradual actuation of the last-mentioned piston by reservoir-pressure and to supply train-pipe-pressure to the combined inlet and outlet of the said chamber upon the actuation of the said piston by train-pipe-pressure, all arranged to operate substantially as and for the purpose set forth.

In testimony whereof, I sign the foregoing specification, in the presence of two witnesses.

FRANKLIN A. PIERCE.
